UNITED STATES PATENT OFFICE.

JAMES K. COCHRAN, OF CARTERVILLE, ILLINOIS.

WIRELESS CHECK-ROW PLANTER.

1,290,913.

Specification of Letters Patent. Patented Jan. 14, 1919.

Application filed July 22, 1918. Serial No. 246,079.

To all whom it may concern:

Be it known that I, JAMES K. COCHRAN, a citizen of the United States, residing at Carterville, in the county of Williamson and 5 State of Illinois, have invented new and useful Improvements in Wireless Check-Row Planters, of which the following is a specification.

It is a well known fact that considerable 10 difficulty is experienced at the present time with markers and planters for corn and other seed, in view of the fact that the wire is usually employed in conjunction with the planter, which wire is engaged by the dropper operating means on the planter, knots or other obstacles being provided at spaced intervals along the wire, the operating means for the planter engaging such obstacles and operating the dropper when so engaged.

20 To overcome this defect I have constructed a planter adapted to operate altogether independently from any exterior means such as a wire, whereby a tremendous amount of labor is saved, together with the inaccuracies 25 accruing from the wire method of planting.

Another objection to the present style of marker is that the same provides for no means of adjusting, whereby a field of other than rectangular shape may be planted, the 30 rows being planted perfect in every respect.

In view of the latter difficulty I have constructed in conjunction with positive operating means for a planter, a marker which is provided with means permitting of an 35 adjustment of the same whereby any irregular field may be planted, the rows appearing regular in every respect.

To accomplish the above objects I have constructed a planter as disclosed in the accompanying sheet of drawings, in which:—

Figure 1 is a side elevation of a corn planter and hill marker, with my wireless check row dropper attached thereto.

Fig. 2 is a plan view of the device as 45 shown in Fig. 1.

Fig. 3 is a detailed view of my operating means for the marker and dropper for the planter, attached to the hub of the planter.

Fig. 4 is a side elevation of this attachment.

Fig. 5 is a detailed view thereof.

Fig. 6 is a view showing this operating means detached from the hub.

Fig. 7 shows a lever applied to the operating means whereby the marker and planter 55 may be adjusted in such a manner as to lay

out and plant regular rows of seed in an irregular field.

Fig. 8 is a detailed view showing the marker, and

Fig. 9 is a view disclosing the links and lever whereby the operating means are connected to the marker and planter.

Referring to the reference characters applied to the drawings it will be seen that 1 65 is the corn planter provided with a frame 2 and wheels 3 and 3' connected together by means of an axle 4. Connected to the hub 5 of the wheel 3 is a cylindrical member 6 secured to such hub 5 by means of set screws 7. 70 The hub 6 is provided with a circumferentially extending groove 6' in which a lever 9 is adapted to seat at its lower end. The lever 9 is provided with a reduced or knife portion 10 adapted to be moved so as to engage 75 ratchets 11 on the cap member 12 when said member is to be adjusted. It will be seen that the upper end of this lever operates in a slot 50 formed in a bracket 51 and this slot is provided with a reduced portion at 80 one end in which the lever normally lies so as to be out of engagement with said ratchets. When the member 12 is to be adjusted the lever is moved into the wide part of the slot so as to engage the ratchets and 85 then by moving said lever said member may be moved to the desired extent.

Secured to the cap member by means of bolts 13 is a U-shaped member 14 having its ends extending outwardly from the member 12. Projecting beyond the base of the cap member 12 is a member 16, which projects through the cap 12 and is formed at its inner end with an eccentric 17 adapted to engage a pawl 18 whose inner end is pivoted to the 95 periphery of the cap 12 and being adapted to engage a ratchet mechanism 19 with its free end, such ratchet 19 comprising the outer edge of a plate 20 mounted around the inner end of the cylindrical member adjacent the cap 12. A bar 21 extends from the planter 1 to a position adjacent the hub 5. A lever 22 is pivotally secured at 23 to the bar 21 and is adapted to be engaged at its lowermost end by the outer arm 15 of the 100 U-member 14, causing it to rock upon its pivot 23 whereby to move a rod 24 connecting the outer end of the lever 22 to the dropping attachment provided within the planter 1, operated by means of the crank 105 arm 25. A short arm 26 is provided above the pivot point of the lever 22 and is secured

to such lever and is adapted by means of a link connection 27 to operate a lever 28 pivoted to the bar 21 at 29.

Pivots secured to the outer end of the 5 lever 28 is the marker 29 adapted to act against the spring 30. As will be noted the marker 29 is adapted to work within a guide arm 31 which also serves as a guard for the marker.

10 Having now described the construction of my device it will be seen that in operation the corn planter upon being moved will cause the wheels 3 and 3' to be rotated, consequently revolving the hub 5 together with 15 the attached cylinder 6 and cap member 12, to which the U-shaped member 14 is secured.

The arm 15 will engage the lower end of the lever 32, causing the upper end thereof to be rocked and operating the dropping 20 mechanism of the planter at predetermined intervals, by means of the rod 24 connecting the upper end of the lever 22 to the crank arm 25, operating the dropping mechanism.

The arm 26 will be moved every time the 25 member 14 engages the lever 22 and by means of the link connection 27 will exert an upward push to one arm of the lever 28 pivoted at 29, causing a consequential depression of the opposite arm. As this opposite arm is pivotally connected to the marker 30 29 and the latter is capable of sliding movement, it will be obvious that the same will be depressed and caused to perform its proper function.

35 It will be seen that I have by means of the pawl and ratchet 18 and 19, as well as the pawl operating eccentric 17, provided means for allowing the planter to be moved backward or forward without operating the corn dropping mechanism, nor the marking device. This arrangement is particularly valuable in going-to and coming from the field 40 to be planted, by throwing the planter and marker out of operating engagement.

45 When now the field is of irregular shape and consequently the rows of each succeeding line are shorter or longer, it will be seen

that I have provided means whereby the rows may be planted in such a manner as to permit of an even dropping of the seed 50 and marking of the hills, whereby regular rows are made which are vitally necessary for proper cultivation, irrigation and maximum production to the acre. It will be seen that this latter object may be accomplished 55 by means of the ratchet 11 which is engaged by the knife edge 10 of the lever 9.

It will of course be understood that I do not desire to limit myself to operating means for a corn planter and hill marker, 60 which must necessarily be secured to the hub, but I believe myself to be entitled to protection which would enable me to construct an operating means such as disclosed in Fig. 3, positioned along any part of the 65 axle.

Having now described my invention what I desire to claim is:—

A corn planter comprising seed dropping means, a marker located adjacent said 70 means, a socket member detachably connected to the axle of the planter, a cap member rotatably carried by said socket member and having an inwardly extending flange provided with ratchet teeth, a ratchet wheel 75 secured to said socket member, a pawl carried by the cap member and engaging said ratchet wheel, a hand operated member having an eccentric thereon carried by said cap member, said eccentric being adapted to 80 engage the pawl to move the same out of engagement with the ratchet wheel, a hand operated lever rotatably mounted on the socket member and having a member adapted to be moved into engagement with the 85 teeth on the cap member for adjusting said member on the socket member when the pawl is moved to inoperative position by the eccentric, a trip on said cap member and means operated by said trip for actuating 90 the dropping means and the marker.

In testimony whereof I affix my signature.

JAMES K. COCHRAN.
